CLAIM

I claim the ornamental design for a computer input device, as shown and described.

DESCRIPTION

FIG. 1 is a perspective view of a mouse and dock, showing my new design;

FIG. 2 is a front elevational view thereof;

FIG. 3 is a rear elevational view thereof;

FIG. 4 is a right-side elevational view thereof;

FIG. 5 is a left side elevational view thereof;

FIG. 6 is a top plan view thereof; and,

FIG. 7 is a bottom plan view thereof.

The broken lines having equal segments represent portions of the article that form no part of the claimed design.
